US0D1053816S

(12) **United States Design Patent** (10) **Patent No.:** **US D1,053,816 S**
(45) **Date of Patent:** **** Dec. 10, 2024**

(54) **ADAPTER HOUSING**

(71) Applicant: **Shenzhen CheYang Technology Co., Ltd.**, Shenzhen (CN)

(72) Inventor: **Hengbin Tian**, Shenzhen (CN)

(73) Assignee: **Shenzhen CheYang Technology Co., Ltd.**, Shenzhen (CN)

(**) Term: **15 Years**

(21) Appl. No.: **29/880,515**

(22) Filed: **Jul. 24, 2023**

(51) LOC (14) Cl. **14-01**

(52) U.S. Cl.

USPC **D14/217**; D14/433

(57) **CLAIM**

The ornamental design for an adapter housing, as shown and described.

DESCRIPTION

FIG. 1 is a front perspective view of an adapter housing, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

The broken lines in the drawings illustrate the portions of the adapter housing, which form no part of the claimed design.

1 Claim, 8 Drawing Sheets
